DAIMLER-MOTOREN-GESELLSCHAFT, OF WURTTEMBERG, GERMANY, A CORPORA-
TION OF GERMANY.

RADIATOR FOR INTERNAL-COMBUSTION ENGINES.

Application filed January 14, 1925. Serial No. 2,455.

To all whom it may concern:

Be it known that I, FERDINAND PORSCHE, a citizen of the Republic of Czechoslovakia, residing at Stuttgart-Unterturkheim, Wurttemberg, Germany, have invented certain new and useful Improvements in a Radiator for Internal-Combustion Engines, of which the following is a specification.

This invention relates to coolers or radiators of the kind in which the temperature is regulated with the aid of a thermostat or thermostats controlling the flow of the hot cooling water, or of the water to be cooled through the cooler or radiator, and the invention consists in so devising the side parts or lateral members of the cooler or radiator, or of its casing, that they can serve as conduits for said water, either directly or indirectly, that is to say, said side parts or lateral members may serve themselves as water-conducting means, or separate pipes may be provided therein.

Another feature of the invention consists in arranging the thermostat or thermostats in the said passages or pipes, as is more fully described hereinafter with the aid of an example, illustrated in the accompanying drawing which shows diagrammatically a vertical cross-section through a cooler or radiator devised according to this invention.

The hot water arriving from the internal combustion engine, or from the motor, flows into the cooler or radiator through the pipe *b* which terminates within the top thereof. *c* denotes the cooling pipes proper which are surrounded by a casing or frame. Now, in contradistinction to known constructions, the side-parts or lateral members *d* and *e* of this casing or frame are hollow and form channels or passages or, more precisely, bypasses for the cooling-water which, thus, flows through the cooling-pipes proper, as well as these latter which are opened or closed more or less by thermostatic valves *f* and *g* arranged therein, as shown.

When the temperature of the water becomes higher than desired, the passages or channels *d* and *e* are correspondingly throttled by the thermostatic valves and a correspondingly larger amount is, conse-

quently compelled to take its way through the cooling pipes proper *c*, the water being, therefore, cooled correspondingly lower. If, however, the temperature of the cooling water sinks below the degree desired, the thermostats operate in the reverse way, the throttling being now correspondingly diminished, so that more water is flowing through the channels *d* *e* and less through the pipes *c*.

The water flows from the top-chamber of the cooler into the pipes *c* and the channels *d* *e*, and the three currents re-unite then in the lower chamber from which the cooled water flows off through the pipe *h*.

The channels *d* and *e* are, in the example shown, provided in the side-parts of the cooler which are hollow for that purpose, but instead of these side-parts themselves separate tubes may be employed which are arranged within the same, the thermostatic valves being, then, of course, arranged in said tubes, as will be clear without a separate illustration and a separate detailed description.

I claim:

1. A cooler or radiator for internal combustion-engines comprising, in combination, a cooler casing having hollow side-parts adapted to serve for the conduction of a part of the cooling-water; the usual cooling pipes in said casing and located between said side-parts, and a thermostatic valve arranged in said hollow side parts to directly control the flow of the water through the said side-parts, as set forth.

2. A cooler or radiator for internal combustion-engines, comprising, in combination, a cooler casing having hollow side-parts adapted to serve for the conduction of a part of the cooling-water; the usual cooling pipes in said casing and located between said side-parts, and thermostatic valves arranged in the latter and adapted to directly control the flow of the water there-through, as set forth.

3. A radiator for internal combustion engines comprising a casing with cooling pipes therein, the side portions of said casing being hollow to form water channels

open at top and bottom, a water inlet pipe entering into the casing above the cooling pipes, a water outlet below said cooling pipes, there being restricted passages 5 through the side portions, and thermostatic valves arranged in said channels to directly control the flow of water therethrough.

In testimony whereof I affix my signature in presence of two witnesses.
